CARTRIDGE-DEFLECTING MEANS FOR
SELF-LOADING REPEATING FIREARMS

Frederick L. Humeston, Hamden, Conn., assignor to Western Cartridge Company, New Haven, Conn., a corporation of Delaware

Application December 4, 1941, Serial No. 421,606

6 Claims. (Cl. 42—3)

The present invention relates to improvements in self-loading repeating firearms, and relates more particularly to means for such firearms whereby ejected cartridge-casings will be deflected away from the person of the marksman.

It may here be noted that self-loading repeating firearms so violently eject cartridge-casings that there is grave danger that the marksman will be struck by such cartridge-casings or at least will have his vision blurred, on occasion, by an ejected cartridge-casing momentarily interrupting the line of sight.

One of the objects of the present invention is to provide superior cartridge-deflecting means for self-loading repeating firearms, which means may be relied upon to effectively deflect cartridges away from the person of the marksman without unduly complicating the mechanism of the firearm.

Another object of the present invention is to provide a self-loading repeating firearm with superior cartridge-deflecting means which will supplement the normal ejection-means in directing ejected cartridge-casings in a harmless path.

A further object of the present invention is to provide superior cartridge-deflecting means for self-loading repeating firearms and so constructed and arranged as to dynamically supplement the normal ejection-means in such firearms and effectively and positively drive the ejected cartridge-casing in a direction away from the person of the marksman.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in side elevation of a self-loading repeating firearm embodying the present invention;

Fig. 2 is a broken view of the central portion of the firearm and showing the same partly in side elevation and partly in vertical central-longitudinal section with the parts in the positions which they assume at the instant of the discharge of the firearm;

Fig. 3 is a top or plan view of the structure of Fig. 2;

Fig. 4 is a broken top or plan view substantially corresponding to Fig. 3, but showing the parts in the positions which they assume when

the breech-bolt has been retired substantially the length of a cartridge-casing;

Fig. 5 is a top or plan view substantially corresponding to Figs. 3 and 4 but illustrating the parts in substantially the positions which they assume when the ejected cartridge-casing engages with the deflecting-abutment of the action-slide during the forward movement of the latter;

Fig. 6 is a broken transverse sectional view taken on the line 6—6 of Fig. 5;

Fig. 7 is a top or plan view of the breech-bolt unit detached;

Fig. 8 is a broken view in central-longitudinal section taken on the line 8—8 of Fig. 7;

Fig. 9 is a transverse sectional view taken on the line 9—9 of Fig. 7; and

Fig. 10 is a broken perspective view of the rear portion of the action-slide, and viewing the same mainly toward the rear and inner face thereof.

The particular self-loading repeating firearm herein chosen for purposes of illustrating the cartridge-deflecting means of the present invention includes in the main, a stock 15, a receiver 16, a trigger-plate 17, a barrel 18 and a barrel-cover or hand-guard 19. The receiver 16, trigger-plate 17 and barrel 18 are rigidly secured together and are preferably formed of high-grade steel, and the stock 15 and barrel-cover or hand-guard 19 are preferably formed of wood or other suitable heat-insulating material.

The barrel 18 is rigidly attached to the band-like forward end 20 of the receiver 16, and has the usual axial bore 21 extending longitudinally therethrough. Immediately to the rear of its band-like forward end 20, the receiver 16 is cut away to form an ejection-opening 16a opening mainly upwardly and partly laterally from the hollow interior of the receiver. The rear end of the bore 21 in the barrel 18 is reamed or otherwise shaped to provide a cartridge-chamber 22 in the usual manner of firearm-barrels.

Reciprocating in the upper portion of the hollow interior of the receiver 16, is a breech-bolt 23 of substantially-cylindrical form which also has oscillatory movement for being locked and unlocked with respect to the receiver 16 in a manner generally similar to that employed in the well-known Garand military rifle. Adjacent its forward end, the said breech-bolt 23 is provided with two oppositely-extending lateral locking-lugs 24 and 25 formed integral with the said breech-bolt. The locking-lugs 24 and 25 of the breech-bolt 23 are respectively engageable with

from the bore 21 of the barrel 18 will pass through the gas-passage 39 with the effect of driving the piston 40 rearwardly until the rear face of its head 40a strikes the forward face of the tubular stop-member 42. This rearward movement of the piston as just described, while but of short length, will drive the action-slide 30 rearwardly against the tension of the breech-closing spring 36 until the said action-slide reaches the limit of its rearward travel or to about the point represented by the broken line A in Fig. 5.

As soon as the action-slide starts rearwardly under the impulse of the piston as above referred to, the contours of the cam-recess 28 of the said action-slide will first cause the breech-bolt to be turned slightly in a clockwise direction when viewed from the front with the effect of disengaging the locking-lugs 24 and 25 of the breech-bolt from the complementary locking-abutments 26-26 of the receiver 16. The turning movement of the breech-bolt as just described will effect its rotation into substantially the position in which it is indicated in Fig. 6, so that both the cartridge-ejector 49 and the cartridge-extractor 53 will also be shifted with the said breech-bolt.

Following the unlocking of the breech-bolt as above described, the continued rearward movement of the action-slide 30 under the impulse imparted to it as previously described, will carry the said breech-bolt 23 rearwardly with great rapidity and since the cartridge-extractor 53 moves with the said breech-bolt, the cartridge-casing 44 or its equivalent will be drawn rearwardly out of the cartridge-chamber 22. For purposes of description, the breech-bolt and the cartridge 44 may be assumed to have now reached the positions in which they are shown in Fig. 4.

As soon as the forward end of the cartridge-casing 44 clears the rear end of the barrel 18, the spring-pressed cartridge-ejector 49 will be free to swing the forward end of the said cartridge-casing upwardly and to the right and about the extractor-nose 51 of the cartridge-extractor 53 as a center. The rearward travel of the breech-bolt 23 and the parts carried thereby is so rapid, however, that both the said breech-bolt and the action-slide 30 will have been moved to the limit of their rearward travel and will have rebounded forwardly to substantially the positions in which they are shown by full lines in Fig. 5 when the cartridge-casing 44 has swung substantially into the position in which it is represented by full lines in Fig. 5. Under these conditions, the action-slide as well as the breech-bolt will be moving forwardly and the forwardly-facing cartridge-deflecting abutment 60 of the said action-slide will strike the cartridge-casing 44 and positively drive the said cartridge-casing forwardly and to the right along a path of flight substantially indicated by the broken lines B in Fig. 5 and hence away from the person of the marksman and from his line of sight.

To achieve the effects above referred to, the cartridge-deflecting abutment 60 of the action-slide 30 is extended into a position crosswise of the firearm so that it will be struck by the cartridge-casing when the same is thrown upwardly and outwardly by the combined actions of the cartridge-ejector 49 and the cartridge-extractor 53. In other words, the action-slide 30 or its equivalent is so shaped with respect to the path of flight of the cartridge, as mainly determined by the positions of the parts 49 and 53, as to be

engaged by the cartridge-casing to deflect the same forwardly and to one side as above described. Furthermore, the best results are secured when the tension of the ejector-spring 50 is carefully predetermined so that the cartridge-casing 44 will not be "flipped" thereby into the position represented by full lines in Fig. 5, until the action-slide 30 and its abutment 60 are traveling forwardly under the combined effects of rebound and the breech-closing spring 36.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

- 20 1. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 30 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing against the cartridge-deflecting abutment of the said action-slide.
- 35 2. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 40 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing against the cartridge-deflecting abutment of the said action-slide.
- 45 3. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 50 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly
- 55 4. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 60 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly
- 65 5. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 65 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly
- 70 6. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 70 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly
- 75 7. A self-loading repeating firearm-structure including in combination: a receiver having an ejection-opening; a breech-bolt reciprocating in the said receiver; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and operatively connected to the said breech-bolt for shifting the same and in a manner permitting limited relative movement between the action-slide and breech-bolt, the said action-slide having a forwardly-facing cartridge-deflecting 75 abutment extending substantially crosswise of the ejection-opening in the said receiver; spring-means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly

by the forward movement of the said action-slide.

3. A self-loading repeating firearm-structure including in combination: a receiver having an upwardly-opening ejection-opening; a breech-bolt reciprocating in the said receiver beneath the said ejection-opening therein; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and reciprocating to one side of the path of movement of the said breech-bolt, the said action-slide being operatively connected to the said breech-bolt for shifting the same and in a manner permitting limited relative movement between the action-slide and breech-bolt, the said action-slide having a forwardly-facing cartridge-deflecting abutment extending transversely of the firearm-structure and crosswise of the upwardly-opening ejection-opening in the said receiver; breech-closing spring means urging the said action-slide forwardly; and actuating-means effective upon the discharge of the firearm to retire the said action-slide rearwardly; the said extractor and the said ejector being positioned on the said breech-bolt to throw a cartridge-casing against the cartridge-deflecting abutment of the said action-slide.

4. A self-loading repeating firearm-structure including in combination: a receiver having an upwardly-opening ejection-opening; a breech-bolt reciprocating in the said receiver beneath the said ejection-opening therein; an extractor carried by the said breech-bolt; an ejector carried by the said breech-bolt; ejector-spring means also carried by the said breech-bolt and urging the said ejector forwardly relative to the said breech-bolt; an action-slide associated with the said receiver and reciprocating to one side of the path of movement of the said breech-bolt, the said action-slide being operatively connected to the said breech-bolt for shifting the same and in a manner permitting limited relative movement between the action-slide and breech-bolt, the said action-slide having a forwardly-facing cartridge-deflecting abutment extending transversely of the firearm-structure and crosswise of the upwardly-opening ejection-opening in the said receiver; breech-closing-spring means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly by the forward movement of the said action-slide.

5. A self-loading repeating firearm-structure including in combination: a receiver having an upwardly-opening ejection-opening; a breech-bolt reciprocating in the said receiver beneath the said ejection-opening therein; an extractor carried by the said breech-bolt; an ejector carried by the said breech-bolt; ejector-spring means also carried by the said breech-bolt and urging the said ejector forwardly relative to the said breech-bolt; an action-slide associated with the said receiver for reciprocation to one side of the path of movement of the said breech-bolt and formed with an upwardly-and-inwardly-inclined lug projecting over the said breech-bolt to a point closely approaching the vertical-longitudinal center thereof, the said lug having a forward face extending substantially transversely of the said breech-bolt to provide a cartridge-deflecting abutment; breech-closing-spring means urging the said action-slide forwardly; and actuating-means effective upon the discharge of the firearm to retire the said action-slide rearwardly; the said extractor and the said ejector being positioned on the said breech-bolt to throw a cartridge-casing against the cartridge-deflecting abutment of the said action-slide.

6. A self-loading repeating firearm-structure including in combination: a receiver having an upwardly-opening ejection-opening; a breech-bolt reciprocating in the said receiver beneath the said ejection-opening therein; an extractor carried by the said breech-bolt; an ejector carried by the said breech-bolt; ejector-spring means also carried by the said breech-bolt and urging the said ejector forwardly relative to the said breech-bolt; an action-slide associated with the said receiver for reciprocation to one side of the path of movement of the said breech-bolt and formed with an upwardly-and-inwardly-inclined lug projecting over the said breech-bolt to a point closely approaching the vertical-longitudinal center thereof, the said lug having a forward face extending substantially transversely of the said breech-bolt to provide a cartridge-deflecting abutment; breech-closing-spring means urging the said action-slide forwardly; and actuating-means effective upon the discharge of the firearm to retire the said action-slide rearwardly; the said extractor and the said ejector being positioned on the said breech-bolt to throw a cartridge-casing into the path of the cartridge-deflecting abutment of the said action-slide, and the said ejector-spring means being tensioned and thereby timed to throw a cartridge-casing into the path of the cartridge-deflecting abutment of the said action-slide after the same has completed its rearward movement and during the forward travel of the said cartridge-deflecting abutment to cause the ejected cartridge-casing to be positively driven forwardly by the forward movement of the said action-slide.

FREDERICK L. HUMESTON.
